UNITED STATES PATENT OFFICE.

SALMON B. ROWLEY, OF PHILADELPHIA, PENNSYLVANIA.

DESIGN FOR FRUIT-JARS.

Specification forming part of Design No. **6,886**, dated September 16, 1873; application filed July 12, 1873.
[Term of Patent 14 years.]

To all whom it may concern:

Be it known that I, SALMON B. ROWLEY, of the city and county of Philadelphia, State of Pennsylvania, have invented a Design for a Preserve-Jar, of which the following is a specification:

My design for a preserve-jar is fully illustrated by the accompanying drawing, in which Figure 1 represents an exterior elevation of the said jar, and Fig. 2 a sectional view of the upper portion of the same.

The body A of the jar is cylindrical, it having vertical sides *a a*, merging into curves *b b*, by which the diameter is gradually reduced at the top or neck, and the lower corners *c* of the jar are in the present instance rounded; but this is immaterial, and forms no part of the

design. The cover B of the jar projects slightly beyond the upper curved portion or neck *b*, has rounded corners *d*, and a circular projection, *e*, above the latter, the said cover being either plain or provided with ribs *f*.

I claim—

The design for a preserve-jar, substantially as described, and as represented in and by the accompanying drawing.

In testimony whereof I have signed my name to this specification in the presence of two subscribing witnesses.

SALMON B. ROWLEY.

Witnesses:

WM. A. STEEL,
HARRY SMITH.
